[57] CLAIM

The ornamental design for a front face of a vehicle wheel, as shown and described.

DESCRIPTION

FIG. 1 is a frontal view of the front face of a vehicle wheel according to my novel design; and,

FIG. 2 is a perspective view of the front face of a vehicle wheel according to my novel design, with the broken line showing for illustrative purposes only and forming no part of the claimed design.

1 Claim, 2 Drawing Sheets

FIG. 1

FIG. 2
